METHOD OF HUSKING CEREALS

Albin Barra, Danzig, Free City of Danzig

Application November 18, 1931, Serial No. 575,916
In Germany November 24, 1930

1 Claim. (CL. 83—29)

This invention relates to a method of removing in a continuous operation the husk from cereal grains of all kinds, which is valueless for the digestion. There have been a great number of attempts to realize this object.

Apart from the known husking, brushing and scrubbing processes it has been proposed to move the cereal grains in the moistened state relatively to one another under the application of pressure and heat, with the object, when the grains strike against resistances or striking surfaces, of loosening the husk on the cereal grains or of removing it from them.

According to the invention the husk is loosened far more effectively by causing the moistened cereal grains to rub against one another under the influence of gravity only. Experience has shown that in this way the husks become completely loosened from the grains without 20 splintering or breaking.

The material coming from the husking apparatus represents a mixture of husked grains and the removed husk. For separating these two constituent parts any of the known milling processes may be employed. Thus, for instance, the material may be washed in a primitive manner with the object of flushing the husks from the grains in the washing operation. The grains then pass to a drying plant and are then subjected either directly to the milling process or in 30 certain cases after being again passed through the process according to the invention to the usual milling process.

The washing of the grains after leaving the 35 husking apparatus may with certain moisture conditions, certain biological properties of the material and the like be eliminated, so that the material passes directly from the husking apparatus to a drying plant or a brushing plant.

For carrying out the husking operation the 40 vertical mill so much used in the milling art is employed, in which the cereal is introduced through a hopper at the top and is withdrawn at the bottom. The husking operation is thus 45 carried out in a vertical container, through which the grains travel under gravity from top to bottom. A slowly running rake-like stirrer, which does not mechanically affect the grains, provides that this downward motion of the 50 grains shall proceed uninterruptedly.

The invention is illustrated in the accompanying drawing, in which the operation and the construction of the husk loosening apparatus are shown diagrammatically.

55 On its way from the silo S the only cleansing

machine through which the grain is passed is the magnetic separator and sorter R. From the latter the grain passes first into a washing and wetting machine I of suitable construction where it is treated in a drum revolving in water, where 60 it remains sufficiently long for the husks of the grain to become loosened and softened. The grain is at the same time washed during this operation, the adhering dirt, sand, dust and the like being loosened from the grain and washed 65 away. In this machine the husks are still left adhering to the grains. The duration of the treatment and the suitable temperature of the washing water are ascertained by experiment and depend to a certain extent on the place of 70 origin and quality of the grain. The grain passes thence into the husk loosening machine II, the construction of which is more particularly described below. In this machine the grain travels, under the action of gravity only, from 75 top to bottom, during which passage the separate grains rub against one another and strip off the husk. The grain which has been freed from the husk, although wet, is internally perfectly hard and unaffected. The grain after being thus treated passes from there into the re-washing apparatus, the machine III, where it is again washed, and thence into the drying apparatus IV, where it is dried by suitable devices in perforated drums. When they leave the last 85 drum the grains are completely dry, the husk having become completely separated from the grain.

The passage of the grain which has been moistened in I through the apparatus II constitutes the essential feature of the invention. 90 The re-washing device, the machine III, may be omitted, if the condition of the grain appears to make a second washing and rinsing superfluous. In that case the material may be conveyed directly to a drying apparatus or a brushing machine, in which the husks, already loosened, are blown away by an air blast or the like. In this case in the drawing the machine II would be followed immediately by the machine IV or 100 a brushing machine with an air blast.

The dried material, after leaving the drying apparatus IV passes, if necessary, into a second husking machine V, which is of similar construction to the machine II and in which any 105 husk particles still adhering to the grain, more particularly the finer cuticles, are removed. The grain then passes into the brushing machine VI, where by means of suitably arranged brushes all bran and gluten still adhering are removed. 110

The grain, now completely cleaned and husked then passes to the usual grinding process.

The interior arrangement of the husk loosening machine II is shown diagrammatically in Fig. 2 in section. The drum *a* is provided at its upper end with a hopper *b* and at the bottom with an outflow *c*. For causing the grains which rub against one another under the action of gravity to travel through the drum *a* a shaft *d* is mounted in the latter, which is provided with rake-like stirring arms *f* and *h*. On these arms a brush or stripper *i* is mounted, the function of which is gently to detach the grains adhering to the wall of the casing *a* and for the rest to convey the grains on the bottom plate *g* of the drum *a* to the outflow *c*. The stirring device which is driven by bevel wheels *e* or the like rotates quite slowly. It is of importance that the stirring device shall have no sharp corners

20

and angles, so as to avoid any mechanical damage to the grains by the stirring device.

A small stirring device may also be provided in the machine V.

What I claim is:

An apparatus for husking cereal grains in a continuous operation comprising: moistening means for softening the husks, a vertical container having an inlet opening for the grains at the top and an outlet opening for the grains at the bottom, a rake-like stirring device disposed in the said container, means for imparting a slow rotary motion to the said rake-like device for moving the grains into rubbing contact with one another and a brush connected to said stirring device and in contact with the wall of the container.
